SYSTEM FOR GENERATION OF POLYPHASE CURRENT

Filed April 24, 1926

UNITED STATES PATENT OFFICE

CLINTON W. HOUGH, OF BOONVILLE, NEW YORK, ASSIGNOR, BY MESNE ASSIGNMENTS,
TO FEDERAL TELEGRAPH COMPANY, A CORPORATION OF CALIFORNIA

SYSTEM FOR GENERATION OF POLYPHASE CURRENT

Application filed April 24, 1926. Serial No. 104,467.

My invention relates broadly to the generation of high frequency currents and more particularly to the generation of polyphase current.

- 5 One of the objects of my invention is to provide a method of generating polyphase current by the action of an electronic stream which is deflected from point to point about a predetermined path.
- 10 Another object of my invention is to provide a system for the generation of polyphase high frequency current wherein an electron stream is moved periodically from one path to another for successively exciting separate 15 electron tube circuits in the output circuits of which polyphase current may be developed.

Still another object of my invention is to provide a system for the generation of polyphase high frequency current in which an electron stream is moved through an orbit for effecting successive paths of conductivity to different electron tube circuits which are thus successively energized for the development of polyphase current.

A still further object of my invention is to provide means for automatically shifting the position of an electron stream about a path in which a plurality of contacts are positioned with separate circuit connections from each of the contacts to independent electron tube circuits the output circuits of which may be connected in three phase manner for the development of three phase current therein.

My invention will be more fully understood from the specification hereinafter following by reference to the accompanying drawings in which:

- 40 Figure 1 diagrammatically illustrates my invention and showing the circuit arrangements between the rotatable electron beam and the several electron tube circuits by which three phase current is developed; Fig. 45 2 illustrates one method which I may provide for rotating the electron beam; Fig. 3 illustrates a modified arrangement which I may provide for securing deflection of the electron stream; Fig. 4 illustrates a magnetic 50 control system for securing rotation of the

electronic beam over a predetermined path in which the several contacts are located; Fig. 5 is a still further modification of a circuit arrangement for moving the electron beam; and Fig. 6 shows a photoelectric cell 55 system embodying the principles of my invention.

My invention contemplates the employment of an electron tube discharge device in which an electron stream is employed in 60 the form of a cathode ray which may be deflected through several different positions in an electron tube in a predetermined path for the successive energization of a plurality of independent electron tube circuits. The electron tube circuits are arranged to be successively energized and the output circuit, 65 Y or delta connected, for the development of three phase current. The three phase current is delivered to the load through a Y 70 or delta coupling system. The periodic deflection of the electron beam or cathode ray in a predetermined path is effected by any suitable shift of an electromagnetic or electrostatic field, as will be described more fully 75 hereinafter. The successive energization of the several independent electron tube circuits at time periods displaced in phase permits the generation of polyphase current at any desired phase displacement, as will be 80 described more fully hereinafter.

Referring to the drawings in more detail, reference character 1 indicates a cathode ray tube having means for developing an electronic discharge in the form of a beam 2 85 which is shiftable about an orbit represented at 3. The deflection or displacement of the electron beam 2 is brought about by various methods, which I have illustrated in the other figures of the drawings.

In Fig. 2 I have shown electrodes 4, 5, 6 and 7 disposed around the cathode stream and connected with a source of alternating current 8, having means 9 and 10 inserted therewith for retarding or advancing the 95 phase of the current delivered to the electrodes 4, 5, 6 and 7. The electrodes are arranged to capacitively affect the electron stream for shifting the stream periodically to the terminals 11, 12 and 13 which extend 100

into the tube 1 and form circuit connections for the grid circuits of electron tubes 14, 15 and 16. The input circuits are each completed through the electron beam 2 by the common connection 17 which connects to the source of cathode rays represented at 18. Each of the tubes 14, 15 and 16 include the grid filament and plate electrodes with the grid and filament electrodes disposed in the several input circuits and the plate and filament electrodes disposed in the output circuits. The output circuit of tube 14 includes inductance 19, while the output circuit of tube 15 has inductance 20 connected therein and these inductances connected in Y to inductance 21 included in the output circuit of electron tube 16. A source of high potential 22 is connected in the common circuit at the central point 24 of the Y connected inductances 19, 20 and 21. These inductances are coupled with Y connected inductances 25, 26 and 27 which connect to a suitable utilization circuit represented generally at 28.

In Fig. 3 I have shown an inductive system for securing deflection of the electron beam 2 about the orbit 3 as distinguished from the capacitive system of deflection represented in Fig. 2. The inductive windings 29 and 30 are arranged with respect to the electron beam 2 in such manner that the electronic stream is moved about the orbit 3 for successively exciting the electron tubes 14, 15 and 16.

In Fig. 4 I have shown a further method of securing the revolving field where the alternating current source 8 connects with the electromagnetic windings 31 and 32 on opposite sides of the tube 1 with a polarized winding 33 which cooperate in such manner that the shifting electromagnetic field in accordance with the periodic current reversals from the alternator 8 tends to revolve the electron stream within the orbit 3.

In Fig. 5 I have shown air core inductances 34, 35 and 36 arranged about the tube 1 for producing the revolving field where winding 36 is normally biased through winding 37 from battery 38. It will be understood that various other methods may be employed for securing the revolving electronic beam.

In the operation of the generating system of my invention the electronic beam is automatically shifted about the orbit 3 for successively energizing the several electron tube circuits and impressing currents in proper phase relation in the Y connected output circuit. These currents are transferred to the Y connected system and supplied to the circuit 28 from which they may be led to an amplifier or any other circuit for utilization.

In lieu of the terminals 11, 12 and 13 which extend into the path of the ray 2 I may provide photo-electric cell elements 39, 40, 41 as shown in Fig. 6 which become successively affected by the moving cathode stream

2. The output of the light sensitive elements may then be used to control an electron tube system for the production of polyphase currents.

While I have described my invention in certain particular embodiments, I desire it to be understood that modifications in detail may be made without departing from the spirit of my invention and that no limitations upon my invention are intended other than are imposed by the scope of the appended claims.

What I claim as new and desire to secure by Letters Patent in the United States is as follows:

1. In a system for generating three phase high frequency current, an electron discharge device, a plurality of means associated with said electron discharge device for deflecting the electron discharge to a plurality of differing positions, a plurality of terminals projecting into said electron discharge device in the path of said electron discharge, a plurality of electron tubes each having grid, filament and plate electrodes, output circuits interconnecting said plate electrodes in polyphase manner and connections between said terminals and said grid electrodes for successively impressing electric charges on said grid electrodes for effecting the generation of polyphase current in said output circuits.

2. A system for generating three phase high frequency current, an electron discharge tube, means for projecting a beam of electrons through said tube, a plurality of terminals within said electron tube, means for successively deflecting said beam of electrons from one of said terminals to another, a plurality of electron tube circuits independently connected with said terminals and a three phase circuit connected with said last mentioned electron tube circuits whereby successive charges may be impressed upon said electron tube circuits for the generation of three phase current therein by the shifting of said beam of electrons from one of said terminals to another.

3. In a system for generating polyphase high frequency oscillation, an evacuated vessel, a cathode ray within said vessel, means for moving said ray to a plurality of different positions, a plurality of electron tubes, each having grid, filament and plate electrodes, input and output circuits interconnecting said electrodes, a plurality of terminals located within said evacuated vessel in the path of said cathode ray and connections between individual ones of said terminals and each of said input circuits, a plurality of inductances connected in said output circuits and associated in three phase manner, and means for successively impressing charges on each of said grid electrodes in accordance with the movement of said ray for generating three phase current in said inductances.

4. A system for generating three phase

- high frequency oscillations comprising, an evacuated vessel, means for producing a beam of electrons therein, means for periodically moving said beam of electrons about a predetermined orbit, a plurality of terminals located within said orbit in the path of said beam, a plurality of electron tubes each having grid, filament and plate electrodes, connections from individual ones of said terminals with said grid electrodes, a common connection for all of said filament electrodes with said source of electrons, a plurality of inductances connected in each of said plate electrodes and arranged in three phase manner whereby successive charges are impressed upon said grid electrodes during the movement of said beam for the generation of three phase high frequency current in said inductances. 5
- 20 5. In a system for generating polyphase high frequency current, an evacuated vessel including a source of electrons, means for projecting said electrons into a beam, means for moving said beam in an orbit, a plurality of terminals located in said orbit in the path of said electron beam, a plurality of electron tubes each having grid, filament and plate electrodes, with the grid electrodes thereof individually connected with one of said terminals, a polyphase connected inductance system having branches thereof connected with said plate electrodes, a polyphase inductance system coupled with said aforementioned inductance system whereby successive charges may be impressed upon said grid electrodes by movement of said electron beam for generating three phase current in said last mentioned inductance system. 30
- 35 6. In a system for generating polyphase high frequency current, an evacuated vessel, means in said vessel for projecting an electron stream in the form of a beam, a plurality of control members located around said vessel for periodically deflecting said beam to a plurality of different positions, electrodes mounted in said evacuated vessel for periodically intercepting the said beam, a plurality of electron tubes each having input and output circuits with the input circuit of each of said tubes connected to one of said electrodes, a plurality of inductances connected in three phase manner in said output circuits, a plurality of inductances associated inductively therewith and means whereby each of said input circuits may be successively excited through the action of said electron stream for the generation of three phase high frequency currents in said last mentioned inductances. 45
- 50 7. In a system for generating three phase high frequency current, an evacuated vessel, means for projecting an electron stream therein, a source of alternating current, a plurality of phase determining means located in circuit with said source, means connect- 55
- 55 ed with individual ones of said phase determining means for periodically deflecting said electron stream, a plurality of electron tubes, each having grid, filament and plate electrodes with said plate electrodes connected in a three phase circuit, terminals extending into said electron stream and connected with said grid electrodes whereby successive charges are imparted to said grid electrodes for generating three phase current in said three phase circuit. 60
- 65 8. A system for generating three phase current comprising independent electron tubes each including grid, filament and plate electrodes, a tube system including an emitter of cathode rays and a plurality of targets arranged in an orbit with respect to said emitter, a circuit extending between each of said filament electrodes, a source of potential and said emitter, an independent connection between each of said grid electrodes and a selected one of said targets, a three phase circuit interconnecting said plate electrodes, and means for successively shifting said cathode rays to each of the electrodes in an orbit for successively energizing the grid electrodes of said tubes from said source of potential and generating three phase current in said three phase circuit. 70
- 70 9. In testimony whereof I affix my signature. 75
